UNITED STATES PATENT OFFICE.

EDGAR WEBSTER SUMMERS, OF PITTSBURGH, PENNSYLVANIA.

CAR-TRUCK SIDE FRAME AND JOURNAL-BOX.

1,190,480.

Specification of Letters Patent.

Patented July 11, 1916.

Application filed January 12, 1916. Serial No. 71,779.

To all whom it may concern:

Be it known that I, EDGAR WEBSTER SUMMERS, a resident of Pittsburgh, in the county of Allegheny and State of Pennsylvania, 5 have invented a new and useful Improvement in Car-Truck Side Frames and Journal-Boxes, of which the following is a specification.

This invention relates to side frames for 10 railway car trucks and journal box therefor.

One object of the invention is to provide a railway car truck side frame of the arch bar type and a journal box so constructed 15 that the latter can be secured to the ends of the side frame without the use of journal box bolts.

Another object is to provide a railway car truck side frame of the arch bar type and 20 a journal box directly connected thereto and so constructed that the neutral axes or centers of gravity of the tension and compression members of the truck side frame intersect vertically over the axis of rotation 25 of the axle and as close down to the same as possible.

A further object is to so construct the side frame as to permit the column posts to be secured to the arch bars by machine 30 riveting.

The invention comprises the combination and arrangement of parts hereinafter described and claimed.

In the accompanying drawings Figure 1 35 is in part a side elevation and in part a longitudinal vertical section of a truck side frame and journal box embodying the invention; Fig. 2 is a plan view of the same; Fig. 3 is a section on the line 3—3 Fig. 1; Fig. 4 is a plan view of the journal box; Fig. 5 is a side elevation of the same; and Figs. 6 and 7 are diagrammatic views illustrating the stresses set up in the end portions of the tension and compression members 45 of an old type of arch bar truck and in the design of truck frames shown in Fig. 1, respectively.

The truck side frame is of the arch bar type having an upwardly bowed or arched 50 compression member 1 and a downwardly bowed tension member 2, the latter having its central portion, as at 3, formed on the arc of a circle or catenary curve, and with the end portions extending from said 55 curved portions as true tangents. The tension and compression members are prefer-

ably formed of rolled flanged sections and as illustrated are of I-beam section, placed with their webs horizontal and their flanges vertical. At their end portions some of the 60 flanges of these members are cut away so as to permit the webs to come into contact, and said members are secured together by rivets 5 extending through said webs. In the angle between the compression and tension members, is the gusset member 6, shown as a casting, although, if desired, it may be formed of a pressed plate or a forging, and which is secured to the tension and compression members by rivets 7. The end 70 portions of said tension and compression members are bent downwardly on a curve at the point of intersection of their neutral axes or centers of gravity, said point being indicated at 8, and have their outer ends 75 inclined downwardly at the same angle from the vertical as the inclined portion of the tension member 2, thereby forming on the lower face of the end portion of said frame an upwardly converging obtuse angle 80 with its apex rounded or curved, as shown in Fig. 1, in order that the point of intersection of the neutral axes or centers of gravity of the arch bars may be brought directly above the center of rotation of the 85 axle. In order that the neutral axes of the tension and compression members can intersect directly above the axis of rotation of the axle, it is necessary to bend the ends of said tension and compression members on a 90 curve struck about a center located in the vertical plane of the axis of rotation. Such intersection of the neutral axes can not be obtained by the use of bars bent at an angle. This is made clear by the diagrams Figs. 5 95 and 6, in which Fig. 5 illustrates an old type of arch bar frame, and Fig. 6 illustrates the principle of the frame of Fig. 1. As shown in Fig. 5 where the lower arch bar 2 is bent at an angle, the neutral axes *a* of the compression member and *b* of the tension member intersect at the point *c*, which is outside of the plane of the center of rotation, the latter being indicated by the vertical line *d*.

The load is applied at *c*, in the direction of 105 the vertical arrow *e*. The horizontal distance from *d* to *e* will vary according to the thickness of the tension and compression members. Assuming these to be $1/2$ inch thick and 5 inches wide, the distance from *c* to *d* will be 110 $21/32$ of an inch. The load therefore acts eccentrically on an arm $21/32$ of an inch long.

Assuming the load to be that of a modern high capacity freight car, to-wit., 34,250 lbs., and acting upon a lever arm 21/32 of an inch, it produces a moment of 22,476 5 lbs., and as the section modulus of arch bars of the dimensions assumed is .416, it results in a fiber stress of 54,000 lbs. per square inch, which is approximately the breaking point. When, however, the arch bars are bent on a 10 curve around a center f located in the vertical plane of the center of rotation, the neutral axes a and b are made to intersect directly above the center of rotation, as indicated in Fig. 6. Consequently there is no 15 eccentric loading whatsoever, and the only stresses produced in the arch bars are compression in the upper arch bar and tension in the lower arch bar, there being no bending moment whatsoever, and no fiber stresses induced corresponding to the fiber stresses above 20 specified due to the eccentric loading where the neutral axes of the arch bars do not intersect in the vertical plane of the axis of rotation. At their central portions the tension 25 and compression members are united by a combined column post and spring seat member, which comprises in a single integral casting the vertical column post portion 9, the bottom or spring seat portion 10 and a 30 top connecting portion 11, which fits in between the tension and compression members and is suitably secured thereto as by rivets, as illustrated. Spring plank members 13 are secured to this casting, such as by 35 bolts 14. The springs rest upon the bottom portion 10 of this casting, and the vertical portions are provided with the usual bolster guides and brake hanger brackets, all as are common in car trucks.

40 One of the novel features of the present application is in having a journal box so constructed as to be secured directly to the end portion of the truck side frame without the use of journal box bolts. As shown, the 45 journal box 16 has its top roof-shaped with a rounded apex to fit into the obtuse angle formed in the lower face of the end portions of the side frame, the same being inclined or sloping symmetrically in opposite directions 50 from its central longitudinal line, so as to have a firm bearing against the lower face of the end portion of the side frame. The apex of the box is curved on a radius whose center of rotation is located in a vertical plane 55 lying in the axis of rotation of the axle and the top surface of said box is cored out to form ribs and to provide a cavity at its central portion for the head of the rivet 5. The top of the box is provided with perforated 60 bosses 18 for receiving rivets 19 which extend through the same and the adjacent parts of the side frame and serve to rigidly secure the journal box to the side frame. The outer one of these rivets 19 passes 65 through the end portions of the webs of

both the tension and compression member and also serves as a means for securing said members together, while the inner one of these rivets passes through the web of the tension member and through a flange of the 70 gusset member 6 and therefore also serves as a means for securing the gusset member to the tension member. To permit access for upsetting this inner rivet, the web of the compression member and the adjacent portion of the gusset member 6 are provided with openings 20 for the insertion of a suitable riveting tool. The holes through the bosses 18 open into pockets 21 formed on the inside and at the upper corners of the journal box, so that the inner heads of the rivets 19 do not interfere with the wedge and brass.

By constructing the top of the box with oppositely inclined surfaces, as shown, the 85 center of rotation of the axle 22 is brought vertically directly below the point of intersection of the neutral axes of the tension and compression members, and up as close as possible to the point of said intersection. 90 The box is rigidly held in place by means of the rivets 19, without use of journal box bolts, as is ordinarily the practice in arch bar trucks. To assist in holding the box in position, and particularly against stresses 95 lengthwise of the side frame, a connection in the form of a tie bar member 23 is formed between the lower portion of the journal box and the truck side frame. As shown, this tie-bar member 23 has its inner end secured by rivets 24 to the depressed central portion of the tension member and has its outer end secured by one or more rivets 25 to a lateral perforated ear or lug 26 on the lower portion of the journal box. The journal box preferably is provided with a lug 26 on each side, and the sloping top surfaces are equal on both sides of the central longitudinal plane of the box, so that said box will interchangeably fit at either end of 100 the side frame.

The journal box illustrated is shown as formed as a casting, but obviously it can be of the built-up pressed variety without departing from the spirit of the invention.

115 The column post member is so formed as to permit of its attachment to the arch bars by machine riveting, that is by a machine which acts by pressure instead of by repeated blows. The column post portion 9 120 in horizontal cross section is of general channel shape, with one of the flanges, to-wit, flange 30, wide or deep, while the other flange 31 is relatively shallow or narrow, so as to permit ready access of the jaw of the 125 riveting machine to the lower end of rivet 32 which is driven through the upper arch bar and the upper portion of the column member. At its lower end the column post member is provided with a pocket 33 so lo- 130

cated that the rivets 24 extend through the web of the lower arch bar normal to the plane of the latter, said pocket being open on its upper side so as to permit access of one 5 jaw of the riveting machine to the upper ends of these rivets.

In the construction illustrated all journal 10 box bolts are dispensed with, and the journal box itself is secured directly to the truck side frame. By having the top of the journal box formed sloping, as shown, it is possible to bring the center of rotation of the axle directly underneath the point of intersection of the neutral axes of the tension 15 and compression members and close up to the latter.

The form and construction of the different parts can be materially modified without departing from the invention as covered 20 by the claims hereinafter following. Obviously the side frame can be formed as a casting, instead of being built up, as illustrated.

What I claim is:—

1. A truck side frame of the arch bar type 25 comprising a compression member and a tension member having their end portions united, a journal box having its top fitting against and riveted directly to the end portions of said arch bar, and a tie bar member secured to the lower portion of said journal box and to the depressed central portion of the tension member.

2. A truck side frame of the arch bar type comprising a compression member and a 35 tension member having their end portions united, a journal box having its top fitting against the end portions of said arch bars and provided with perforated lugs for riveting the same directly to the arch bars, and 40 a tie bar member secured to a perforated ear on the lower portion of the journal box and to the central depressed portion of the tension member.

3. A truck side frame of the arch bar 45 type comprising a compression member and a tension member having their end portions united and with the end portions of both members bent and having a tangent inclined downwardly on an angle corresponding to the inclination of the tension member, and a journal box having its top formed to fit in said angle and being directly secured to the side frame.

4. A truck side frame of the arch bar type 55 comprising a compression member and a tension member having their end portions united and with the end portions of both members bent and inclined downwardly on an angle corresponding to the inclination 60 of the tension member, a journal box having its top formed to fit in said angle and being directly secured to the side frame, and a tie bar member secured to the lower portion of said journal box and to the depressed central portion of the tension member.

5. A truck side frame of the arch bar type comprising a compression member and a tension member having their end portions united and with the end portions of both members bent and having a tangent inclined downwardly on an angle corresponding to the inclination of the tension member, and a journal box having its top formed to fit in said angle and being provided with 70 perforated bosses for directly securing the same to said arch bars. 75

6. A truck side frame of the arch bar type comprising a compression member and a tension member having their end portions united and with the end portions of both members bent and inclined downwardly on an angle corresponding to the inclination of the tension member, a journal box having its top formed to fit in said angle and being provided with 80 perforated bosses for directly securing the same to said arch bars, and a tie bar member secured to a perforated ear on the lower portion of the journal box and to the central depressed portion of the tension member. 85

7. A truck side frame of the arch bar type comprising a compression member and a tension member having their end portions united and having the end portions of both members bent on a curve about a radial 90 point which is vertically under the point of intersection of their neutral axes and inclined downwardly on an angle corresponding to the inclination of the tension member, and a journal box having its top formed to fit in said angle and being directly secured to the side frame. 95

8. A truck side frame of the arch bar type comprising a compression member and a tension member having their end portions united and having the end portions of both members bent on a curve about a radial 100 point which is vertically under the point of intersection of their neutral axes and inclined downwardly on an angle corresponding to the inclination of the tension member, a journal box having its top formed to fit in said angle, and fastening means extending through the top of said box and said arch bars. 105

9. A truck side frame of the arch bar type comprising a compression member and a tension member having their end portions united and having the end portions of both members bent on a curve about a radial 110 point which is vertically under the point of intersection of their neutral axes and inclined downwardly on an angle corresponding to the inclination of the tension member, a journal box having its top formed to fit in said angle, and fastening means extending from the inside of said box through the arch bars. 115

10. The combination of a journal box having its top higher at its longitudinal center 120

90

than at its sides, said top having a curved apex the radius of which has its center of rotation located in a vertical plane lying in the axis of rotation of the journal, and a 5 truck side frame of arch bar type having a tension member conforming to and resting on the top of said journal box.

11. The combination of a journal box having its top higher at its longitudinal center 10 than at its sides, said top having a curved apex the radius of which has its center of rotation located in a vertical plane lying in the axis of rotation of the journal, said top having slopes symmetrically each side of 15 and at an equal angle with the said vertical plane, and a truck side frame of arch bar type having a tension member conforming to and resting on the top of said journal box.

12. A journal box for arch bar trucks having its top higher at its longitudinal center 20 than at its sides, said top having a curved apex the radius of which has its center of rotation located in a vertical plane lying in the axis of rotation of the journal, said box 25 being ribbed on its upper surface.

13. The combination of a truck side frame comprising a compression member and a tension member having their end portions united and bent on a curve and inclined 30 downwardly, and a journal box fitting in said angle and having its top higher at its longitudinal center than at its side and its apex curved on a radius whose center of rotation is located in a vertical plane lying 35 in the axis of rotation of the journal, said radius being of such length as to permit the neutral axes of the tension and compression members of the side frame to intersect vertically over the said axis of rotation of the 40 journal.

14. The combination of a truck side frame comprising a compression and tension member having their end portions united and bent on a curve and inclined downwardly on 45 an angle corresponding to the inclination of the tension member, and a journal box fitting in said angle and having its top sloping symmetrically each side of and at an equal angle with a vertical plane lying in the axis 50 of rotation of the journal and having its apex curved on a radius whose center of rotation is located in said vertical plane, said radius being of such length as to permit the neutral axes of the tension and compression 55 members of the side frame to intersect vertically over the said axis of rotation of the journal.

15. A journal box for arch bar trucks having its top provided with perforated bosses 60 for riveting to a side frame and with a lateral perforated lug at its bottom for the attachment of a tie bar member.

16. A journal box for arch bar trucks having its top inclined from its central longitudinal line in opposite directions and pro- 65

vided with perforations for riveting to a side frame and with lateral perforated lugs at its bottom for the attachment of a tie bar member.

17. A journal box for arch bar trucks having its top inclined from its central longitudinal line in opposite directions and provided with pockets in its upper corners and perforations extending from said pockets through its top wall for receiving securing 70 members.

18. A journal box for arch bar trucks having its top inclined from its central longitudinal line in opposite directions and provided with perforations for riveting to a 80 side frame and with lateral perforated lugs at its bottom for the attachment of a tie bar member, the first named perforations extending into pockets at the upper corners of the box for receiving the inner heads of the 85 rivets.

19. A truck side frame of the arch bar type, comprising tension and compression members having their end portions united and their middle portions separated, and a 90 column post member secured by rivets between the middle portions of said tension and compression members, said column post member being of channel shape in cross section and having one flange thereof of reduced width at its upper end to permit access to the securing rivet.

20. A truck side frame of the arch bar type, comprising tension and compression members having their end portions united 100 and their middle portions separated, and a column post member secured by rivets between the middle portions of said tension and compression members, said column post member at its lower end being provided with an open pocket extending between the sides of said member from the spring seat side and having its bottom sloping downwardly toward the spring seat side to permit 105 access to the securing rivets.

21. A journal box for arch bar trucks having the outer face of its top inclined from its central longitudinal line in opposite directions and having the inner face of its top solid at the central portion to form 115 a bearing for the stop wedge and provided with perforations extending through its top from its upper corners for receiving securing rivets.

22. A journal box for arch bar trucks having the outer face of its top inclined from its central longitudinal line in opposite directions and provided on its inside with pockets in its upper corners and perforations extending from said pockets through 120 its top for receiving securing members, thereby leaving the inner face of said top solid at its central portion to form a bearing 125 for the stop wedge.

23. The combination with an arch bar 130

- side frame, of a journal box upon whose top the end portion of said side frame rests, said journal box being provided on its inside with pockets in its upper corners, thereby leaving the central portion of the top wall solid to form a bearing for the stop wedge, and fastening means having heads seated in said pockets and extending through the top of the journal box and through the side frame.
24. The combination with an arch bar side frame, of a journal box having the central portion of its inside top wall solid to form a bearing for the stop wedge, and provided with perforated bosses at the sides of said solid central portion, and fastening means extending through said perforated bosses and through the side frame.
25. A truck side frame of the arch bar type comprising a compression member and 20 a tension member having their end portions united and forming a journal box seat, and a journal box fitting in said seat and provided with perforated lugs for riveting the same to the end portions of said side frame, 25 the rivet through one of said lugs passing through the tension member of the side frame, and the compression member of the side frame being provided with an opening to permit access to said rivet.
